ELECTRIC RESISTANCE WATER HEATER

Donald B. Miner, Stratford, Conn.

Application July 10, 1947, Serial No. 769,683

10 Claims. (Cl. 219—39)

1

This invention relates to domestic electric water heaters of the resistance type, for use with upright boilers or storage tanks.

An object of the invention is to provide an improved resistance type water heater for use in connection with domestic water boilers or tanks, the said heater being characterized by extremely high efficiency and low cost.

A further object of the invention is to provide an improved electric water heater as above which is so organized as to result in the depositing of a minimum of scale and other solids on the heater walls whereby reliable and trouble-free operation is had over an extended period of use.

Still another object of the invention is to provide an electric heater as characterized above, having an improved mounting for an automatic control whereby the control is readily and quickly removable and replaceable without disturbing the hydraulic system of the heater or boiler.

A still further object of the invention is to provide an improved automatically controlled resistance type electric water heater for use with upright boilers or tanks, wherein a relatively large supply of hot water is produced during the initial heating stage of the heater, prior to the heating means being automatically, temporarily shut-off for the first time.

In accomplishing these objects there is provided by the invention, as illustrated in the specific embodiments thereof described herein, a novel electric heating and heat-exchange structure comprising an elongate tube of non-magnetic metal, preferably copper, for connection at its ends with an upright storage tank or boiler to carry circulating water passing from and to the tank. The metal tube is preferably although not necessarily of larger diameter than the diameter of the pipes between it and the connecting tank. On the outside of the tube and electrically insulated from it but in intimate heat relation therewith, a novel heating coil is provided, consisting of commercial grade copper wire, preferably enamel covered. The copper wire is wound on the tube in spaced convolutions, and considering the rated current or power consumption of the heater, covers a relatively large area of the tube as compared with the area which would be covered for a similar power consumption if wire of high resistance alloy were used for the coil.

An efficient heat-exchange is provided between the copper coil and copper tube by first wrapping the tube with lapped turns of fibre glass fabric tape, over which the copper wire is wound. Aft-

2

er the winding of the copper coil it is coated with a heat resistant impregnating substance such as a silicone varnish, the said varnish serving to anchor the convolutions of the coil and maintain the spacing of the said convolutions, and the varnish impregnating the glass tape insulation and providing a unitary overall assembly of tube, insulation and heating coil, the parts of which are securely maintained in their original predetermined relationship. The fibre glass tape and silicone varnish efficiently electrically insulate the coil from the tube, and also insulate the individual convolutions of the coil from each other.

By this organization I have found that first, an extremely efficient and effective heat exchange is provided between the copper tube and copper coil; second, that heating and cooling of the assembly does not disturb or dislocate the components thereof due to differences in thermal expansion which exist between the copper and insulating material; and third, that for a given wattage input a relatively large heat-exchange area of coil and tube is had. This latter enables a given volume of water to be quickly and efficiently heated by the present improved heater while at the same time relatively low temperatures may exist in the walls of the tube as compared with temperatures encountered in resistance heaters wherein alloy resistance wire is utilized. In consequence of this improved organization and low-temperature heating, boiling, bubbling or distillation at the walls of the heating tube is maintained at an extremely low value or may be non-existent, and therefore, the deposition of scale, minerals and other solid substances on the walls of the tube is largely obviated. By this organization, therefore, the heater maintains a high degree of efficiency and does not clog up in use, especially where hard water is being heated, and a uniform and reliable operation is had at all times, over an extended and long period of use.

By the provision of the efficient heat exchange structure above mentioned, the copper wire resistance coil may be made to carry a current greatly in excess of the rating normally considered safe, without danger of the wire becoming over-heated and burning out, so long as water is present in the tube of the heater. Moreover, by the construction wherein the heat per unit area is maintained at a relatively low value, the likelihood of steam being formed by the heater to cause damage to the water system, should the heater be inadvertently allowed to remain on continuously, is obviated.

In the upper portion of the tube on which the copper heating coil is wound a transverse well is provided, extending into the tube and being permanently sealed thereto so that water cannot escape. The walls of the well are subjected to the heated water which is leaving the top of the tube, and a thermostatic element operatively connected with a circuit-controlling switch for the heating coil is inserted in the well so as to be subjected to the heat of the heated water. The control comprising the thermostatic element and switch means thereof is frictionally held in place by a simple spring clip, and therefore after disconnection of the wires to the switch, the control may be easily and conveniently removed without disturbing the hydraulic system of the heater, or of the tank connected with the heater. Therefore servicing and/or replacement of the control is reduced to a simple operation which may be done quickly and economically.

In one form of the invention illustrated herein a second tube is disposed within the tube on which the coil is wound, so as to be substantially coextensive therewith, and both ends of the second tube are open. At its top the second tube admits the well in which the thermostat control is carried, and I have found that by this organization a greater volume of hot water may be produced during the initial stage of heating of the coil, due to the effect being had of a delayed action of the thermostat. This is accomplished by the cold water which enters the lower ends of the tubes and travels upward in the inner tube, this water remaining relatively cool since it is heated much less than the water in the outer tube. In consequence of this, the average heat to which the thermostat is subjected is less than that which it would experience without the provision of the inner tube. Therefore the thermostat is not caused to operate as soon, and a greater quantity of water will thus be heated during the initial heating interval of the thermostat than would be heated without the use of the inner tube, since the initial heating interval is longer. Also, this is accomplished without raising the temperature setting at which the thermostatic switch will be opened, and therefore the safety factor provided by the thermostat is not altered since it will still respond to the same predetermined temperature as when the inner tube is not employed.

Other features and advantages will hereinafter appear.

In the accompanying drawings:

Figure 1 is an elevational view of the improved heater of this invention, connected with a hot water tank to carry circulating water passing to and from the tank.

Fig. 2 is an axial sectional view of the improved heater.

Fig. 3 is an enlarged fragmentary detail in section of a wall of the heater.

Fig. 4 is a fragmentary view, enlarged, of a connection to one end of the heating coil of the heater.

Fig. 5 is a view like Fig. 2 but showing a modification of the invention wherein a delayed action of the thermostat is had during the initial heating period of the heater, and

Fig. 6 is a transverse sectional view of a water heating tube and a heating coil illustrating another modification of the invention.

Referring to Figs. 1 and 2, the improved electric water heater of this invention comprises a

metal tube 10 which is of non-magnetic metal, preferably copper, the ends of the tube being permanently secured, as by silver soldering, to flanges 11 of reducing fittings 12 which receive pipes 13 and 14 connected respectively to the lower and upper portions of an upright water tank 15. The tube 10 is thus connected to carry circulating water which passes to and from the tank 15.

According to the invention, the tube 10 is wrapped with electrical insulation which is resistant to high temperatures and at the same time has high thermal conductivity, the said wrapping comprising fabric tape 16 formed of glass fibres and wrapped around the tube 10 in overlapping convolutions. Over the wrapped tape 16 a heating coil 17 of copper wire 18 is wound, the said wire being preferably enamel covered and wound in spaced convolutions, and having a relatively great length in view of the wattage of the heater, so as to cover a relatively large area on the outside of the tube 10. The coil 17 of wire 18, whether bare or enamel covered, is coated with a heat resistant electrically insulating varnish having high heat conductivity, such as a silicone varnish, the said coating being shown at 19 Fig. 3, and serving to anchor the wire 18 to the tape wrapping 16. The silicone varnish also impregnates the tape 16 and adheres to the latter to the copper tube 10 whereby the tube, tape and coil are formed into a unitary assemblage.

It will be noted that the copper wire 18 is unsheathed, that is, devoid of any covering of substantial thickness which might appreciably interfere with the transfer of heat from the wire to the tube 10. It is intended that the word "unsheathed" as used hereinafter be construed as defining either a bare wire, or an enameled wire having a coating not exceeding one or two thousandths of an inch, such as is found in commercial grade enameled wire.

Due to the low resistance of the copper wire 18 forming the coil 17, it has a great length for a given wattage input, and therefore covers a relatively large area of the tube 10; as a consequence the input or heat per unit covered area of the tube 10 is relatively low, and the operating temperature of the tube is relatively low. Also, by the provision of the glass fibre tape 16 and silicone varnish coating 19, an effective electrical insulation is provided between the coil 17 and tube 10 and at the same time an efficient exchange of heat is had between the coil and tube. As a result of this latter, the operating temperature of the coil 17 is not greatly different from the temperature of the tube 10, the said temperatures being largely controlled by the temperature of the water inside the tube.

Because of the relatively low operating temperature of the tube 10 for a given adequate wattage rating of the heater, a satisfactorily large volume of water may be heated in a given time with a minimum of bubbling of the water, or distillation of solids from the water and depositing of same on the inner walls of the tube 10. Therefore, especially where the heater is used in conjunction with hard water, the tendency for scales or deposits to be formed on the inner walls of the tube 10 is held to a minimum, resulting in an efficient and reliable heating of water being had over a long and extended period of use of the heater. Also, the temperature differential between the water and the tube 10 and heating coil 17 is maintained at a low value,

so that overheating of the coil is prevented at all times that water is present. Due to the high heat conductivity of the copper of the tube 10 and of the coil 17 and the efficient heat exchange between these, the coil 17 may carry a current greatly in excess of that normally considered safe for copper wire of the size used, without resulting in the wire 18 becoming excessively hot or approaching burnout temperatures. This is true so long as any water exists within the tube 10.

I have found that by this organization, over an extended period of use of the heater, water may be heated more effectively and quickly than when high resistance alloy is used as the resistance wire, due to the lower operating temperature of the coil 17 and tube 10, and the substantially larger area of the tube 10 which is covered by the coil 17 and heated thereby and which area is as a consequence transmitting heat to the water in the tube.

Where nickel alloy (Nichrome) or other high resistance alloys have been used in the past in a heating coil the area covered by the Nichrome coil and which transmits heat to the part carrying the circulating water is considerably less than that provided in the present improved heater, and as a consequence operating temperatures are much higher, resulting in boiling, bubbling and distillation of the water inside of the heating tube. If for the same wattage heater it were attempted to use Nichrome or other similar alloy to cover the same area of tube covered by the novel copper wire heating coil of the present invention, then the cross-sectional area of the Nichrome wire would have to be excessively great to provide the proper wattage, and unless special rectangular shapes were resorted to, a multi-layer coil would have to be employed. This would result in increased fabrication costs, and greatly increased wire costs, and a reduction in the efficiency of heat-exchange between the coil and tube.

Where Nichrome wire is used to cover a smaller tube area, in spite of the shorter length of Nichrome, the cost of the Nichrome wire is greatly in excess of the cost of the greater length of copper wire used herein, in addition to the undesirable effect being had of bubbling, distillation of water, etc. Depositing of solids thus occurs, and is quite marked where hard water is used, and eventually these solids cause a coating or scale on the inside of the heating tube, resulting in a marked reduction of transfer of heat to the water and in general impairing and adversely affecting the efficiency of the heater. Also, such deposits cause the operating temperature of the alloy resistance wire to become higher than that for which the unit is designed, resulting in dangerous temperatures being approached and eventually causing burnout of the resistance coil. Moreover, such higher temperatures are wasteful since for a given thickness of heat insulation they cause more heat to be lost externally of the heater, which heat serves no useful purpose. According to the present invention, however, whereby it is possible to raise the desired quantity of water to the desired temperature by use of lower operating temperatures in the heater, less heat is lost externally of the heater and therefore less heat is wasted or dissipated without serving a useful purpose.

Referring to Fig. 2, the tube 10 and heating coil 17 are wrapped with a thick layer of heat insulation 20 which is enclosed in a metal jacket

21 secured in place by end plates 22 engaging the reducing fittings 12.

In accordance with the invention, for the purpose of effectively controlling the temperature of the heating coil 17 and of the water heated thereby, and to enable quick and convenient servicing of such control, the upper portion of the tube 10 is provided with a transversely extending well in the form of an open-ended tube 23 which passes through the walls of the tube 10 and is silver soldered or otherwise sealed thereto so as to prevent leakage of water therefrom. The tube 23 is of course much smaller in diameter than the tube 10 so that water may circulate through the latter tube upwardly past the tube or well 23.

In the well 23 a thermostat element 24 is located, connected to a switch housing 25 in which a circuit controlling switch 26 is carried for actuation by the element 24. The switch 26 is connected to control the heating coil 17, and connection is made to an exterior current supply through a flexible conduit 27 which is secured to the switch housing 25.

The thermostat element 24, adjacent the housing 25, has an enlarged detent collar 28 having recesses or depressions 29 engageable by spring fingers 30 secured to the tube 23 whereby the element 24 and housing 25 are frictionally retained in place and may be removed when desired by merely applying a pulling force thereto. By this construction, removal of the thermostat 24 and housing 25 does not involve the hydraulic circuit of the heater at all, and may therefore be done in a simple manner and without loss of time for servicing operations if this should be necessary.

Referring to Fig. 4 each end of the wire 18 constituting the heating coil 17 may be wrapped around the eye of a connector lug 31 and soldered thereto, the said lug being electrically connected with lead wires 32 as shown. The lug 31 is disposed to lie flat against the fibre glass tape 19 so that the end portions of the wire 18 are in intimate contact with the tape, thereby preventing overheating of said ends by virtue of the heat transfer to the tube 10 being maintained.

A modification of the invention is shown in Fig. 5, wherein means are provided for causing a delayed action of the thermostat 24 during the initial heating period of the heater. This means comprises a metal tube 33 mounted within the tube 10 and substantially coextensive therewith, both ends of the tube 33 being open and the lower end being supported in the tube 10 by means of struts 34. The upper end of the tube 33 receives and is supported by one end of a tube 23a constituting a well for the thermostat 24, the inner end of the tube 23a being closed as shown. The remainder of the heater shown in Fig. 5 is substantially the same as the heater of Figs. 1 through 4, and like parts have been given like characters.

The operation of the heater of Fig. 5 is as follows: Circulating water entering the lower end of the heater travels upward through the tube 10 and also through the tube 33. This entering water is cold or cool, and as it travels upward in the tube 10 it is heated by the heating coil 17. The water ascending in the tube 33 is not heated as rapidly as the water in the tube 10 and therefore has a lower temperature, and this water of lower temperature comes into contact with the inner end of the well 23a and causes the average temperature of the said well to be less than the

temperature of the well 23 in Figs. 1 through 3. As a consequence, during the initial heating of the heater the thermostat 24 will not be operated to open the circuit of the heating coil 17 as soon as it will in the heater without the inner tube 33. In other words, more heat will be imparted to the water in the tank 15 before the thermostat 24 operates to initially open the circuit of the coil 17, and therefore more hot water will be available for use after initial turning on of the heater. All this is accomplished without raising the cut-off temperature of the thermostat 24, and therefore the safety factor afforded by the thermostat is not adversely effected even though in effect its action is delayed.

Preferably the tube 23a is silver soldered to both the outer tube 10 and the inner tube 33, thereby to provide a metallic connection whereby heat-exchange by conduction may take place between the tubes 10, 23a and 33, resulting in more uniformity in the temperature of the tube 23a and thermostat element 24.

Referring to the modification of the invention shown in Fig. 6, the fibre glass insulation between the copper wire heating coil 17 and the tube 10 is in the form of a single large sheet of fibre glass fabric, the said sheet being wrapped around the tube and the edges lapped to provide a longitudinally extending lapped seam. Preferably, the fibre glass fabric is impregnated with a heat resistant silicone varnish, and is calendered to provide a very smooth surface on both sides. By this organization the application of the insulation to the tube 10 is simplified, and a more uniform condition of heat exchange is provided between the coil 17 and the tube 10 due to the elimination of surface irregularities in the fibre glass insulation. To further improve the heat-exchange between the coil 17 and tube 10 the latter may be coated with silicone varnish prior to application of the fibre glass sheet, and this also simplifies the assembly of the heater since the fibre glass sheet may be adhered to the tube by such coating.

By the provision of the copper wire heating element 17, an advantageous self-regulating effect is had by virtue of the high temperature coefficient of resistance of the copper wire, and therefore there is less likelihood of dangerous overheating in the event of malfunctioning of the thermostat. Also, a quicker heating is obtained during the initial period when the heater is first turned on. For example, when the wire 18 of the heating coil 17 is cold, it has a relatively low resistance, and therefore a higher current will pass through it, causing it to heat relatively quickly. As the temperature of the heating coil 17 rises, the overall resistance of the coil will increase substantially due to the high temperature coefficient of resistance of copper. As a consequence of this latter, the operating current in the coil is reduced in proportion to the rise in temperature, and if the temperature should rise over the normal operating temperature of the unit, due to failure of the thermostat, the reduction of current in the coil 17 will become substantial and tend to act as a safety feature. Thus, a self-regulating effect is had which is not present in heating elements using high resistance alloys.

By virtue of both the coil 17 and tube 10 being made of copper, the thermal expansion of these will be substantially equal, thereby resulting in a desirable mechanical stability of the heating unit

comprising the coil, tube and fibre glass insulation thereof.

Variations and modifications may be made within the scope of this invention and portions of the improvements may be used without others.

I claim:

1. An electric water heater for use with a storage tank, comprising a metal tube having connections at its ends with the said tank to carry circulating water from and to the tank, an electrical coil for heating the tube; a thermostatic control for said coil, said control having an elongate portion to receive heat from the heated water; and a well for carrying the elongate portion of the control, said well extending transversely into the tube adjacent one end thereof whereby water flows around the well in directions substantially at right angles to the well axis and said well being metallically sealed to the tube and arranged to prevent water in the tube from entering the well, the elongate portion of the control being removable from the well without disturbing the said seal and arrangement.

2. An electric water heater for use with a storage tank, comprising a metal tube having connections at its ends with the said tank to carry circulating water from and to the tank; an electrical coil for heating the tube; a thermostatic control for said coil, said control having an elongate portion to receive heat from the heated water; and an open-ended tube for carrying the elongate portion of the control, said tube extending transversely into and through the water tube whereby water flows around the open-ended tube in directions substantially at right angles to the axis thereof and said open-ended tube being sealed adjacent its ends to opposite walls of the water tube, said elongate portion of the control being removable from the transverse tube without disturbing the said seals.

3. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; means for heating the walls of the outer tube; and a thermostatic control for said heating means, said control being arranged in heat-exchanging relation with water in both the inner and outer tubes whereby the action of the control is delayed during initial operation of the heater, said heater being operable with the tubes thereof in a substantially vertical position.

4. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; means for heating the walls of the outer tube; and a thermostatic control for said heating means, said control being arranged in heat-exchanging relation with water in both the inner and outer tubes whereby the action of the control is delayed during initial operation of the heater, said heater being operable with the tubes thereof in a substantially vertical position and the thermostatic control being located adjacent the upper ends of the tubes.

5. A water heater for use with a storage tank,

comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; means for heating the walls of the outer tube; and a thermostatic control for said heating means having an elongate portion for exposure to heat; and a well for carrying said elongate portion, said well extending transversely into the inner and outer tubes whereby the action of the control is delayed during initial operation of the heater, said heater being operable with the tubes thereof in a substantially vertical position, and said well being sealed to the outer tube and arranged to prevent water in the tubes from entering the well, the elongate portion of the control being removable from the well without disturbing the said seal and arrangement.

6. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; means for heating the walls of the outer tube; and a thermostatic control for said heating means having an elongate portion for exposure to heat; and a closed-end tube for carrying said elongate portion, said tube extending transversely into the inner and outer tubes whereby the action of the control is delayed during initial operation of the heater, said heater being operable with the tubes thereof in a substantially vertical position, and said closed-end tube being sealed to the said outer tube and arranged with its open end out to prevent water in the inner and outer tubes from entering the closed-end tube, the elongate portion of the control being removable from the closed-end tube without disturbing the said seal.

7. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; metal means for heating the walls of the outer tube; and a thermostatic control for said heating means, having an elongate portion for exposure to heat; and a well for carrying said elongate portion, said well extending transversely into the inner and outer tubes whereby the action of the control is delayed during initial operation of the heater, said heater being operable with the tubes thereof in a substantially vertical position, and said well being metallically sealed and joined to the inner and outer tubes to provide for conductive heat exchange between the well and said tubes.

8. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating

water passing from and to the tank; means for heating the water in contact with the inner wall of one tube substantially at the said contact; and a thermostatic control for said heating means, said control being arranged in heat-exchanging relation with water in both the inner and outer tubes whereby the action of the control is delayed during initial operation of the heater, said heater being operable with the tubes thereof in a substantially vertical position.

9. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; means for heating the water in contact with the inner wall of one tube substantially at the said contact; and a thermostatic control for said heating means, having an elongate portion for exposure to heat; and a well for carrying said elongate portion, said well extending transversely into the inner and outer tubes whereby the action of the control is delayed during initial operation of the heater, said heater being operable with the tubes thereof in a substantially vertical position, and said well being sealed to the outer tube and arranged to prevent water in the tubes from entering the well, the elongate portion of the control being removable from the well without disturbing the said seal and arrangement.

10. A water heater for use with a storage tank, comprising a pair of elongate tubes located one within the other and extending substantially co-extensive with each other, the inner tube being open at both ends and the outer tube being adapted for connection adjacent its ends with said tank to enable the tubes to carry circulating water passing from and to the tank; means for heating the water in contact with the inner wall of one tube substantially at the said contact; a thermostatic control for said heating means, having an elongate portion for exposure to heat; and a well for carrying said elongate portion, said well extending transversely into the inner and outer tubes whereby the action of the control is delayed during initial operation of the heater, said heater being operable with the tubes thereof in a substantially vertical position, and said well impeding water flow through the tube at whose wall the water is heated, to a relatively less extent than it impedes water flow through the other tube.
